Primary Examiner — Ricky Pham*(74) Attorney, Agent, or Firm* — C.G. Mersereau; DeWitt, Mackall, Crounse & Moore, S.C.(57) **CLAIM**

The ornamental design for a cooking pot, as shown and described.

DESCRIPTION

FIG. 1 is a perspective view of a cooking pot showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is a reference perspective view thereof showing that the cooking pot is mounted on a cooker.

The dashed lines shown are included for the purpose of illustrating unclaimed portions of the article and form no part of the claimed design.

The dot-dot-dash lines are included for the purpose of illustrating environment of the article and form no part of the claimed design.
